FIG.4.

FIG. 5.

Inventor
John A. McCall
By R.S. & A.T. Lacey
Atty's:

UNITED STATES PATENT OFFICE.

JOHN A. McCALL, OF TOPEKA, KANSAS.

FLAMBEAU.

SPECIFICATION forming part of Letters Patent No. 233,425, dated October 19, 1880.

Application filed July 15, 1880. (No model.)

To all whom it may concern:

Be it known that I, JOHN A. McCALL, a citizen of the United States, resident at Topeka, in the county of Shawnee and State of Kansas, have invented certain new and useful Improvements in Flambeaux; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object to furnish a device to be used as a flambeau or torch in processions and on other occasions when lights and exhibitions of fire-works are desired. It consists in the construction and arrangement of the several parts, hereinafter fully described, and pointed out in the claims.

In the drawings, Figure 1 is a vertical section. Fig. 2 is a vertical section of a part made on an enlarged scale. Fig. 3 is a plan. Fig. 4 is a cross-section on line *x x*, Fig. 1. Fig. 5 is a modification, and Fig. 6 is a cross-section on line *y y*, Fig. 2.

Heretofore in the construction of flambeaux or torches of the class to which this invention belongs there has been employed a powder-box with an oil-chamber attached to its side, and having the wick-tube bent laterally from the oil-chamber over the top of powder-box and over the powder-pipe. There was also a blow-pipe carried into the powder-chamber and inserted in a central pipe, through which the powder was blown upward to the flame; but the arrangement in such devices was attended with much danger when gun or other explosive powder was employed, owing to the close proximity of the flame to the top of the powder-box and to the body of the powder. In my device these dangers are obviated by reason of the construction of the main casing with the oil-chamber, placed immediately above the powder-chamber, and having the central powder-tube carried through the oil-chamber, and in placing the flame at a much greater distance from the body of the powder.

a represents a casing, which is supported on a handle or staff, *b*. The staff may be made in jointed and separable sections, if desired,

so that it can be lengthened or shortened, as may be desired.

The casing *a* is divided by the horizontal partition *a'* into upper and lower chambers, *a²* *a³*. The upper chamber, *a²*, is designed to hold oil or other burning-fluid, which is drawn through the wick-tubes *c*, projecting from the upper side of the casing *a*. The oil-receptacle *a²* can be filled through the opening closed by the plug *a⁴*.

The series of wick-tubes *c* are arranged around the central point of the top of the casing *a*, and have their tops or outer ends converged or inclined inward toward each other, so that the several wicks will throw their flames together and form a single flame. The three or more flames combined into one will give a much greater light than when all are burning but separately.

I have shown only three wick-tubes, as this is the most convenient number; but two or four, or even more, may be employed, if desired.

d is a tube, open at both ends, and is placed in the casing *a*, and is held in place by the partition *a'* and the top *a⁵*. It is hermetically soldered around where it passes through the partition *a'* and the top *a⁵*, so that the fluid in the chamber *a²* cannot leak out past it. The lower open end, *d'*, of the tube *d* is carried nearly to, but does not quite touch, the bottom *a⁶* of the chamber *a³* in the casing *a*. The upper end, *d²*, of this tube is carried through the top *a⁵* at a point centrally between and equidistant from the wick-tubes *c*, and its open end *d³* is about in the same horizontal plane with the outer ends of the wick-tubes.

e is a blow-pipe, which has its upper end in the chamber *a³*, while its other end is carried down through the bottom *a⁶* into the staff *b*, and is bent outward through the side of said staff, and is provided with a mouth-piece, *e'*, arranged conveniently for the person carrying the torch. The upper end, *e²*, of this pipe is closed, as shown. A short distance below the upper end, *e²*, there is attached an arm or tube, *e³*, which is carried through the side of, and is bent downward within, the tube *d*. There is provided by this arrangement a small valve-chamber, *e⁴*, in the upper end of the pipe *e*.

f is a valve seated in the pipe *e*, just below

the opening into the tube e^3 . Its function is to prevent air being blown down the tube d , out through the tubes e^3 and e , while it permits air to be blown through the tubes e and e^3 and out through the tube d . When tube e is blown into, the valve rises into the chamber e^4 and opens the tube e^3 . When the blast of air is stopped the valve drops back onto its seat and closes the upper end of the tube e .

10 g is a spring-clasp held by staples and loops to the side of the casing a , and is adapted to hold Roman candles or other similar fire-works. It is open on one side, so that it will expand and hold candles and other articles of different sizes.

15 In Fig. 5 is shown a short sleeve, h , which slides over and fits snugly on the upper end, d^2 , of the tube d . Its upper end, h' , is flared outward, and has placed therein an inverted conical-shaped plug, h^2 , so disposed as to provide a narrow space around it and between it and the flared lip h' . The plug h^2 is supported in its position by short plugs h^4 , secured thereto, and leaning against or fastened to the 20 sides of the mouth h^2 , as shown.

25 The under portion of the casing a is made hopper-shaped, as shown, so that the lower end of the chamber a^3 is contracted nearly to the size of the lower end of the inner tube, d . The chamber a^3 is provided near its upper end with an orifice closed by a removable plug, a^7 , through which the powder to be burned is put. Suitable wicks are provided and inserted in the wick-tubes c , and the chamber a^2 is filled 30 with oil or other suitable burning-fluid. Within the chamber a^3 there is put any suitable powder designed to give increased flame or color to the light of the torch. The powder should be filled in till it rises above the lower 35 end of the inner tube, d .

40 In the operation of the device the combined flames of the series of wicks in the tubes c give a brilliant light.

45 By blowing into the tube e the powder in the chamber a^3 will be forced upward through the tube d , and, entering the flame from the wicks, will give a light according to the kind of powder used. If gunpowder be used the flame will be a sudden flashing up to a great 50 height, giving a beautiful and startling exhibition.

The valve f , the moment the blast of air is stopped, falls and closes the tube and prevents any sucking back of the current, and thereby 55 obviates all possibility of accident by fire being drawn down the tube d .

The attachment h is employed when it is desired to spread and increase the breadth of

the flame. This attachment is also of great value when no powders are used.

60 By gently blowing in the tube e the flame of the wicks can be spread laterally, greatly increasing its breadth and effect on the eye of the spectator.

65 A torch-easing constructed without a powder-chamber could have the pipes e and d united so as to form a single air-tube from the mouth-piece to the wicks; but such a construction could be used only for blowing air to spread the flame. This object is attained 70 by the tubes constructed as shown, while additional to that result the throwing of the powder is secured when desired.

75 The staff or handle is made in sections, sleeved one upon the other, and onto a flange on the lower end of the casing, as shown, so that the parts can be disconnected for storing away when not in use or for packing in small compass for transportation or other purposes.

80 Having thus described my invention, what I claim, and desire to secure by Letters Patent, is—

1. A flambeau or torch composed of the casing inclosing an oil-chamber at its upper end and a powder-chamber below at its lower 85 end, the central tube disposed with its lower end near to the lower end of the powder-chamber, and with its upper end extended through the oil-chamber, and having its open mouth arranged between and about on the same plane 90 with the mouths of the wick-tubes, the blow-pipe furnished with a mouth-piece on its lower end and having its upper end carried into the powder-chamber and connected with the central tube, and the valve seated in the upper end 95 of the blow-pipe, substantially as and for the purposes set forth.

2. The combination of the casing provided with loops, and the candle-holder g , provided with hooks and adapted to be attached to the loops on the side of the casing a , substantially 100 as and for the purposes set forth.

3. The combination of the tube d and wick-tubes with sleeve h , furnished with a flaring mouth, h' , and provided with the inverted 105 conical plug h^2 , so disposed as to provide a space surrounding it and between it and the flaring sides of the sleeves, substantially as and for the purposes set forth.

110 In testimony that I claim the foregoing I have hereunto set my hand.

JOHN A. McCALL.
